UNITED STATES PATENT OFFICE.

JOHN H. IRWIN, OF BEARDSTOWN, ILLINOIS.

IMPROVEMENT IN LAMPS.

Specification forming part of Letters Patent No. 33,588, dated October 29, 1861.

To all whom it may concern:

Be it known that I, JOHN H. IRWIN, of Beardstown, in the county of Cass and State of Illinois, have invented a new and Improved Lamp; and I do hereby declare that the following is a full, clear, and exact description of the same, reference being had to the annexed drawings, making a part of this specification, in which—

Figure 1 is a vertical central section of a lamp constructed according to my invention; Fig. 2, shows the plane of section; Fig. 2, a plan or top view of the same; Fig. 3, a detached view of the wick-tube; Fig. 4, a detached vertical section of the wick-tube and deflector, y y, Fig. 2, indicating the plane of section.

Similar letters of reference indicate corresponding parts in the several figures.

To enable those skilled in the art to fully understand and construct my invention, I will proceed to describe it.

A represents a lamp, which may be constructed in any of the known ways or forms, and B is a cap which is screwed into the top of the lamp, and has a flat wick-tube C secured vertically and centrally in it. The upper end of the wick-tube C has an oval plate D attached to it, and this plate inclines down at each side of the wick-tube, as shown in Fig. 1. The form of the plate D is shown clearly by the dotted lines in Fig. 2. The orifice of the wick-tube extends through the plate D.

E is a cone or deflector which is fitted on the cap B and extends up just above the top of the wick-tube C. This cone or deflector has a slot a made in its upper end, the form of which is shown in Fig. 2, the sides and ends being concave or curved inward, as plainly shown at 1 1 1 1 in Fig. 2. The top of the cone E, around the slot a, inclines downward toward the wick-tube, and the slot a is just a trifle above the top of the wick-tube C, as shown in Fig. 1. By this arrange-

ment the cone E is made to deflect the air that passes into the cap against the base of the flame only, and a large volume of air is thereby concentrated at that point and a brilliant illuminating-flame obtained. Another advantage is that all of the oil is burned, none being allowed to escape over the top of the wick-tube C, and no effluvia escapes from the lamp and a comparatively small glass chimney is only required, about one-third ($\frac{1}{3}$) the length of those now used. The plate D directs the air to the outer part of the upper end of the cone and causes the air to be deflected properly or in a concentrated manner against the flame. In fact, the plate D forms, in connection with the top of the cone E, what may be termed an "air-passage" in the upper part of the cone to cause the air to act properly on the flame. (See Fig. 1.)

The lower part of the wick-tube C is slotted vertically at two points 2 2, (shown in Fig. 3,) and the lower part of the metal 3 between the slots 2 2 is bent in the form of a tube 4 to form a bearing for the rod F of the wick-wheels 6 6, which work through the slots 2 2 and act against the wick G. By this arrangement the wheels 6 6 are kept firmly in place and the wick is prevented from becoming entangled with the wheels—a contingency due to the spurs of the wheels penetrating too far into the wick G, caused by a play of the rod D. The bearing 5 effectually obviates this difficulty.

Having thus described my invention, what I claim as new, and desire to secure by Letters Patent, is—

Forming a bearing 4 for the rod F of the wick-wheels 6 6 by turning or bending the part 3 of the wick-tube between the slots 2 2, as and for the purpose specified.

JOHN H. IRWIN.
